Inventor:

Edward L. Morris.

UNITED STATES PATENT OFFICE.

EDWARD L. MORRIS, OF BOSTON, MASSACHUSETTS.

DESIGN FOR A TOY FULMINATE-EXPLoder.

SPECIFICATION forming part of Design No. 13,837, dated April 3, 1883.

Application filed February 9, 1883. Term of patent 7 years.

To all whom it may concern:

Be it known that I, EDWARD L. MORRIS, a citizen of the United States, residing at Boston, in the county of Suffolk and State of Massachusetts, have invented and produced a new and original Design for Toy Fulminate-Exploders, of which the following is a specification, reference being had to the accompanying drawing, forming part thereof.

10 The drawing shows a side view of my design, which consists of representations as herein-after named.

15 A represents a face carried upon a handle, B. The nose is turned up and flattened, and has an indentation, C, which serves the purpose of a receptacle for fulminate. D is the

hammer, containing the representation of a nose and mouth. When the string E is pulled the hammer covers a portion of the face A, changing its features, as shown by the dotted 20 lines, and producing an amusing effect.

What I claim as my design, and desire to secure by Letters Patent, is—

The design for a toy fulminate-exploder, consisting of a face, A, containing the fulminate- 25 receptacle C and a hammer, D, intended to change the features of the face, substantially as shown.

EDWARD L. MORRIS.
